COPYING APPARATUS

Dwight H. Holmes, Harley T. Burgner, and Eugene D. MacEwing, Chicago, Ill., assignors to Iconograph Company, Chicago, Ill., a corporation of Illinois

Application September 17, 1931, Serial No. 563,260
Renewed January 12, 1938

17 Claims. (Cl. 178—6.6)

This invention relates in general to printing by electrical impulses, and while the invention will hereinafter be described as embodied in an office appliance, particularly adapted for the copying or reproduction of typewriting, printing, handwriting, maps, drawings, and other documents, it will be readily apparent that the invention is capable of employment for the printing by electrical impulses to produce original pictures of objects either in black and white or in graduated tones, and may be employed for direct printing, or for the printing at remote points by telephone connection or radio transmission.

One of the important objects of the invention is the provision of an improved process of copying documents and an apparatus for the practice of such process, which will permit rapid reproduction of typewriting, handwriting, printing, maps, drawings and other documents upon any desired receiving paper, and without requiring any special treatments, such for example as photo-sensitive coating of the receiving paper.

Another important object of the invention is the provision of a copying apparatus of the character described, wherein the printing and copying will be accomplished by a plurality of point impressions, which may be all of like intensity and visual effect, so that the copy produced will be even and readily legible, independently of line imperfections in the original from which the copy is being made. By slight alteration in the current control, gradations of printing may be accomplished so that from certain aspects of the invention confinement of patent is not desired in this regard.

Another important object of the invention is the provision of an office copying apparatus, which is, or may be, of compact form and readily portable.

Another important object of the invention is the provision of an apparatus of the character described, which will be wholly automatic in its action, and which will not require particular skill or training for its operation.

Another important object of the invention is the provision of an apparatus of the character described, which may be constructed to provide one, two, three, or more simultaneous copies of a subject matter.

Another important object of the invention is the provision of an apparatus of the character described, the action of which will be of extreme rapidity and certain and even in its impression.

Numerous other objects and advantages of the invention will be apparent as it is better under-

stood from the following description, which, when taken in connection with the accompanying drawings, illustrates a preferred embodiment thereof.

Referring to the drawings,

Figure 1 is an end elevation of an apparatus embodying the present invention;

Fig. 2 is a top plan view thereof;

Fig. 3 is an enlarged plan view of a portion of the perforated sheet in the scanning device;

Fig. 4 is a section taken substantially on the line 4—4 of Fig. 3;

Fig. 5 is a section taken substantially on the line 5—5 of Fig. 7;

Fig. 6 is an enlarged vertical section through one of the magnets at the printing point;

Fig. 7 is an enlarged vertical section through the point printing mechanism, certain of the magnets being shown in section and certain of the magnets being shown in elevation;

Fig. 8 is a partial elevation of the point printing mechanism;

Fig. 9 is a view similar to Fig. 6, showing a magnet of somewhat different construction; and

Fig. 10 is a schematic wiring diagram of the control provided for the point printing mechanism.

The instant embodiment of the invention contemplates the scanning of a document, or other sheet to be reproduced, by an apparatus which divides the area of the sheet into minute sections individually inspected in the scanning, so that each individual section, preferably of an area of about $\frac{1}{64}$ " square, controls point printing upon a receiving sheet in accordance with the scanning.

The scanning device includes a plate arranged over the matter to be copied, and provided with a plurality of perforations arranged in rows transversely of the sheet, as may be observed by comparing Figs. 2 and 3, wherein this perforated sheet is indicated by the reference character 21, and the transverse rows of perforations by the reference characters 22, 23, and 24, it being understood that a considerable number of these rows are provided. The perforations in each row are separated somewhat, and the perforations in the successive rows are progressively offset, as may be observed in Fig. 3.

Relative movement is produced between the sheet to be copied and the plate, this movement preferably being accomplished by moving the scanning device and the plate over the sheet as the scanning progresses. The offsetting of the perforations of the various rows with respect to the perforations of other rows causes each minute

part or section of the sheet being copied to appear separated at a perforation.

A plurality of light beams of narrow width are successively moved or swung transversely of the sheet being copied, and directed through the presented perforations onto the exposed small areas of the original. If these areas be dark, i. e., if matter to be copied is presented at the perforations, point printing is accomplished upon the copy sheet by a magnetically impelled corresponding printing point, the magnetic points being arranged in accordance with the perforations in the plate 21, and the magnets controlled in accordance with the light reflection from the exposed areas at the perforations as the light beams are swung transversely and as the scanning and point printing mechanism is moved longitudinally over the sheets of original and copy.

With this preliminary general explanation of the instant embodiment of the invention, detailed description will now be undertaken.

The apparatus shown on the drawings is mounted upon a suitable base, which may be of any preferred construction, and which is schematically indicated at 31. This base is provided with an upwardly extending fixed bed 32, upon which the document to be copied (indicated at 33) is adapted to be arranged in fixed position. A second bed 34 also extends up from the base 31 and provides a fixed support for the copy sheet 35, upon which reproduction of the original is to be accomplished.

A carriage, generally indicated at 36, is adapted to move longitudinally of the beds 32 and 34, and is provided with rollers 37 and 38, respectively mounted upon tracks 39 of the bed 32 and tracks 41 of the bed 34.

Two scanning devices 42 are mounted on the carriage above the bed 32, each of which is adapted to scan a transverse half of the original sheet. A point printing mechanism 43 is mounted above the bed 34, and provides the printing mechanism for producing imprinting upon the copy sheet in accordance with the scanning devices 42.

The perforated plate 21 is arranged in the carriage in close adjacent relationship to the upper face of the original sheet, and forms the lower part, or perforated wall, of the light chambers of the two scanning devices. The scanning devices are duplicates each of the other, except that one is arranged with its light directing elements at the left of the table or support 32, and the other at the right. A description of one of the scanning devices will be, it is believed, sufficient for an understanding of the two.

A source of light 44 is mounted within the concentrating reflector 45, secured at 46 upon the carriage 36. This source of light directs a confined beam out through an opening 47 and against a flange 48 of a revolving turret 49, which is provided with a plurality of condenser lenses 51, adapted to be successively projected across and to transmit the light beam to a succession of mirrors 52, arranged at the upper ends of levers 53, which are pivoted at 54 on uprights 56, mounted on the carriage 36.

The mirrors 52 reflect the light beam, which is generally indicated in dotted lines at 55, through an opening 56 in the top of a scanning chamber 57.

A photo-electric cell 58 is mounted in this scanning chamber in a pocket 59 out of direct path of the light beam. Each lever 53 and its supported mirror 52 is swung as each condenser lens 51 passes it in the rotation of the turret 49, this be-

ing accomplished in the present instance by cams 61 mounted on the turret, and which engage rollers 62 carried by the levers 53.

Viewing Fig. 2 it will be noted that there is a lever 53 for each row of perforations 22, 23, 24, 5 etc. in the perforated plate, and in the rotation of the turret 49 a light beam is swung from the broken line position indicated at 63 to the broken line position indicated at 64 along each row of perforations and successively along the successive rows.

Rotation is imparted to the turrets 49 from a motor 71, mounted upon a rearward extension 72 of the carriage. The motor shaft 73 is provided with a bevel gear 74, engaging a companion gear 15 75 upon a cross shaft 76, in turn provided with a bevel gear 77 meshing with companion gear 78, the turrets being driven by bevel gears 79 and 81, as may be readily observed from the drawings.

Simultaneously with the rotation of the turrets the whole carriage is moved longitudinally of the document to be copied and of the copy sheet. A worm or screw 80 is fixed in uprights 82, fastened to the base 31, and is in thread engagement through the center of a gear 83, arranged through hub side bearings 84 in the carriage. The gear 83 is adapted to be continuously rotated by a pinion 85 fixed upon the motor shaft 73. Thus geared the carriage is moved in synchronism with the successive projections of the light beam along the successive rows of perforations as the turrets 49 revolve. The swinging of the successive levers 53 occurs in close sequence and the timing is such that the reflection through each perforation may exert its individual influence upon the photo-electric cell.

It may be mentioned that it has been discovered that it is not necessary that there be a direct reflection from the mirror to the area exposed within the perforation and then up to the cell by 40 arrangement of the light beam so that the angle of incidence is equal to the angle of reflection, the apparatus being sufficiently sensitive to permit controlling effect upon the photo-electric cell by the difference between a white and a dark 45 area exposed through the individual perforation.

The point printing mechanism, which has been mentioned, is controlled in accordance with the scanning of the small sectional areas of the original to be copied, comprising a multiplicity of 50 magnets each adapted to operate a printing point by impinging it against a printing ribbon or carbon sheet, the printing points being arranged in accurate accordance with the perforations of the scanning plate 21.

Referring now more particularly to Fig. 1, the printing point mechanism 43 comprises a frame 91 mounted upon the carriage and containing a set of upper magnets 92 and a set of lower magnets 93. The upper magnets 92 are staggered 60 with respect to the lower magnets 93 and control pin rods 94 having bearings through frame parts 95 and 96. The lower magnets 93 control pin rods 97 having bearings through the bottom frame part 96.

The arrangement of these magnets is perhaps best illustrated in Fig. 5 wherein the pin rods 94 are shown in section and the pin rods 97 in plan. It will be noted that the magnets are arranged in transverse rows with the members of succeeding 70 rows offset successively lengthwise of the apparatus, the offsetting being such that overlapping printing impressions are accomplished to reproduce a full line across the sheet.

Each of the magnets of the instant embodiment 75

ment of the invention is provided with two coils, one of which, namely the upper 98, is adapted to impel its printing pin or rod on a printing stroke, and the lower of which 99 is adapted to retard or prevent a printing stroke by opposing the effect of the magnet coil 98.

5 Springs 101 are provided to return the pins or rods to upper position after a printing operation, and the magnet coils 98 of course must 10 overcome the force of the springs 101 in printing.

The current is periodically successively and in proper sequence supplied to the magnet coils 98, and unless the coils 99 be energized under the control of the photo-electric cells, printing occurs at each periodical energization of each 15 magnet coil 98.

Two different magnet and armature constructions are shown on the drawings, one of these being illustrated in Fig. 6 and the other in Fig. 9.

20 The magnet shown in Fig. 6 comprises the upper winding 98 disposed about an internal upper sleeve 102, and the winding 99 about an internal lower sleeve 103. These sleeves are separated by a box 104, within which is mounted a disc 105 25 on a rod 106 which separates the upper armature 107 and the lower armature 108, being interposed between their stems. Internal guide sleeves 109 may be provided if desired.

When current is supplied to the coil 98 the 30 armature 107 is attracted and presses down upon the rod 106, which in turn forces down the pin toward printing position. If current is supplied to the coil 99 under the influence of a photo-electric cell the armature 108 is attracted and 35 printing prevented.

In order to secure certainty of action of the desired rapidity of printing stroke, the current deliveries are so timed that delivery of current to magnet coil 99 is delayed until after completion of the circuit delivering current to the companion coil 98. This permits a quick and early impression of the point if impression is to be permitted.

The magnet structure shown in Fig. 9 comprises an inner member or core sleeve 111, having an annular flange 112, which spaces the upper winding 98 from the lower winding 99. The armatures 107 and 108 in this embodiment of the invention are separated by a non-magnetic rod 50 113, and the action of the magnets is the same as that hereinbefore described.

A printing ribbon, generally indicated by reference character 121, is extended from rollers 122 and 123 carried upon the top of the frame 55 91, this ribbon extending over guide rollers 124 at the top and guide rollers 125 at the bottom. In the operation of the apparatus this ribbon is successively passed over the receiving paper sheet 35, as is usual with typewriter and other similar 60 ribbons.

A detailed showing or description of a ribbon feed is believed unnecessary to the instant invention, it being mentioned however that the ribbon passes between the printing pins and the 65 sheet 35 in the instant embodiment of the invention.

As has been stated, electric current is successively delivered to the upper coils 98 of all of the printing magnets independently of the scanning influence and in timed relation to the scanning 70 actions.

Referring to Fig. 2, reference character 131 indicates an electric generator mounted upon the carriage and driven by the motor shaft 73. This 75 generator, through suitable wiring to be present-

ly described, delivers actuating current to the successive magnets through a distributor mechanism. This distributor mechanism comprises two discs 132 fixed in upright position and loosely embracing a shaft 136 mounted in end bearings 5 137. A sleeve 135 is mounted upon the shaft 136 for independent rotation, and arms 134 are fixed upon the sleeve to rotate with it and move electric contacts 138 into successive engagement with contacts provided in the two discs 132. The 10 sleeve 135 with its arms 134 is rotated continuously during the operation of the apparatus by gearing, which will now be described.

A bevel gear 139 is fixed on the sleeve 135 and meshes with a bevel gear 140 upon the end of 15 a shaft 141 which carries a bevel gear 142 in mesh with a gear 133 upon shaft 73. Successive engagement between the contacts 138 and the contacts on the discs 132 successively delivers 20 energizing current to the coils 98, as will be presently more fully described.

An interruptor for the circuits is provided to prevent delivery of current to any of the magnet coils between the active scanning actions. This interruptor comprises two discs 143, fixed in position with the shaft 136 extending through their centers. Two arms 146, having contacts 157, are fixed upon the shaft 136 in such position that the contacts 157 engage successively insulated segments of the disc 143 included in the magnet 30 circuits. The shaft 136 is rotated in timed relation with the rotation of the sleeve 135, by a bevel gear 144 fixed upon the shaft 136, and a companion bevel gear 145 fixed upon the shaft 141, already described. 35

The mechanical devices employed to control delivery of current to the magnet coils 99 (which are the coils controlled by the photo-electric cell 58), except for the wiring which is more particularly illustrated in Fig. 10, include the distributor and interruptor already described, contacts 173 being provided upon the arms 134, adapted to engage appropriately arranged and insulated contacts, mounted in the discs 132, and individually controlling the circuits to the 40 coils 99 of the several magnets 92.

Because of the number of scanning actions and the number of magnets accordingly provided, the distributor and interruptor are each divided into two duplicated units, one disc 132 and one 50 disc 143 being associated with and controlling half of the magnets 92.

A wiring diagram is illustrated in Fig. 10 and referring to this figure reference characters 151 and 152 indicate respectively positive and negative main line wires from a source of electricity, which in the instant embodiment is the generator 131. Wire 151 is connected to contact 138 of arm 134. The contact 138 successively engages contacts 153 arranged circumferentially of 60 the disc 132 and individually connected by wires 154 with upper coils 98 of the pin magnets 92. The coils 98 are in turn connected by wires 155 with segments 156 of disc 143.

The arm 146 is provided with a contact 157 65 which successively rides over the segments 156 and is in turn connected to wire 152. Motivating current is thus provided successively to the coils 98 of the magnets 92 except when the contact 157 is in engagement with the insulations 70 158 between the segments 156, which occurs between scanning of successive transverse rows of perforations 22, 23, 24, etc.

A current is distributed or supplied successively to the coils 99 by circuits as follows: 75

The photo-electric cell is indicated at 58 and it will be understood that this cell completes a circuit for an appropriate magnet coil 99 at the presentation of each white area in the perforations in the usual and known manner. Wiring diagram is not shown on the drawings for this since it is well known to those acquainted with photo-electric cells and photo-electric cell control. It may be mentioned, however, that the 10 current change in the photo-electric cell occasioned by the reflection of the scanning device is amplified by a suitable amplifying device indicated generally by reference character 171.

Positive current is delivered through wire 172 15 to a contact 173 of rotating arm 134. Contact 173 is adapted for successive engagement with contacts 174, which are mounted on disc 132. Each of the contacts 174 is connected by a wire 175 with one side of the winding 99 in its companion magnet 92. The other side of the coil 99 is in turn connected to the interrupter and through the interrupter to the negative side of the source of power to complete the circuit. On the wiring diagram shown in Fig. 10 this return 20 is through the wires 155, segments 156, contact 157 and wire 152.

It will be apparent that since the connection between the scanning device and the point printing mechanism is entirely electrical these units 30 might be widely separated and the electric impulses transferred by telephone or by radio transmission, it only being necessary that the movement of the mechanical portions of the device be started and maintained with accurate timing 35 and proceed at equal speeds.

Also it will be apparent, it is believed, that the scanning may be accomplished by the projection of any desired image upon a ground glass, or even from a three dimensioned object.

40 Also in the operation of the apparatus the force of impact of the pins in the printing may be controlled to give shaded results by varying the current in the coils 99 in accordance with variation in the reflection to the photo-electric cells.

45 The embodiment of the invention hereinbefore described is particularly adapted for fast, economical, and satisfactory copying in an organized apparatus, which may be of portable character 50 and of compact form. The invention however has other and more general use and application.

It is thought that the invention and many of its attendant advantages will be understood from the foregoing description, and it will be apparent 55 that various changes may be made in the form, construction and arrangement of the parts without departing from the spirit and scope of the invention or sacrificing all of its material advantages, the form hereinbefore described being 60 merely a preferred embodiment thereof.

We claim:

1. A reproducing apparatus, comprising in combination a support for the subject matter to be reproduced, a photo-electric cell, means successively directing light to successive areas of said subject matter for reflection to said photo-electric cell, and a printing mechanism comprising a plurality of printing points positioned to duplicate the arrangement of said areas, an inking 65 medium for said points, and a plurality of magnets electrically controlled from said electric cell and in accordance with the reflection from said confined areas for actuating said printing points.

70 2. A reproducing apparatus, comprising a scanning device and a point printing mechanism, said

scanning device comprising means for directing a beam of light successively to points spaced transversely of the matter being scanned and successive beams of light to intermediate transversely spaced points, a photo-electric cell receiving reflections from said points, and said point printing mechanism comprising a plurality of pointed members positioned to duplicate the arrangement of the points to which the light beams are directed, a plurality of magnets connected one to each of said members and arranged for control by said photo-electric cell in the order and arrangement of the points scanned by said scanning device. 10

3. A reproducing apparatus, comprising a scanning device and a point printing mechanism, said scanning device comprising a non-rotating rectangular plate perforated to provide rows of openings, the openings of each row being spaced transversely of the plate and the openings of successive rows being offset progressively longitudinally of the matter being scanned in overlapping relation, a photo-electric cell, and means directing a beam of light successively along said rows of perforations. 15

4. A reproducing apparatus, comprising a scanning device and a point printing mechanism, said scanning device comprising a plate perforated to provide rows of openings, the openings of each row being spaced transversely of the plate and the 20 openings of successive rows being offset progressively longitudinally of the matter being scanned in overlapping relation, a photo-electric cell, and means directing a beam of light successively along said rows of perforations, said means including 25 a light concentrating member movable transversely of said rows of perforations.

5. A reproducing apparatus, comprising a scanning device and a point printing mechanism, said scanning device comprising a plate perforated to 40 provide rows of openings, the openings of each row being spaced transversely of the plate and the openings of successive rows being offset progressively longitudinally of the matter being scanned in overlapping relation, a photo-electric cell, and means directing a beam of light successively along said rows of perforations, said means including 45 a light concentrating member and a plurality of reflecting mirrors, one for each row of perforations, for receiving a beam of light from said light concentrating member. 50

6. A reproducing apparatus, comprising a scanning device and a point printing mechanism, said scanning device comprising a plate perforated to provide rows of openings, the openings of each row being spaced transversely of the plate and the 55 openings of successive rows being offset progressively longitudinally of the matter being scanned in overlapping relation, a photo-electric cell, and means directing a beam of light successively along said rows of perforations, said means including a light concentrating member and a plurality of mirrors one for each row of perforations, said mirrors swinging individually to move the beam of light lengthwise of its row of perforations. 60

7. A reproducing apparatus, comprising a scanning device having means for directing a confined beam of light to successive minute portions of the matter being scanned, a photo-electric cell influenced in accordance with said scanning device, a point printing mechanism comprising a plurality of magnets, each provided with a printing point, said printing points being positioned to duplicate the arrangement of the re- 70

75

spective minute portions of the matter being scanned, means supplying said magnets successively with impelling current to move the printing points in a printing direction in sequence in accordance with the movement of said light beam, and an electric control for modifying the action of said magnets in turn controlled by said photo-electric cell.

8. A reproducing apparatus, comprising a scanning device having means for directing a confined beam of light to successive minute portions of the matter being scanned, a photo-electric cell influenced in accordance with said scanning device, and a point printing mechanism comprising a plurality of magnets, each provided with a printing point, said magnets being arranged in rows transversely of a receiving sheet, the members of successive rows being offset successively in overlapping relation.

9. A reproducing apparatus, comprising a scanning device having means for directing a confined beam of light to successive minute portions of the matter being scanned, a photo-electric cell influenced in accordance with said scanning device, and a point printing mechanism comprising a plurality of magnets, each provided with a printing point, said magnets being arranged in rows transversely of a receiving sheet, the members of successive rows being offset successively in overlapping relation, and said magnets also being disposed in a plurality of planes at different distances from said receiving sheet.

10. A machine for producing printed copies of typewritten, printed and other documents comprising, in combination, a first supporting means for a document to be copied, a second supporting means for a sheet to be printed, a scanning device associated with said first supporting means and comprising a screen positioned over said document and perforated to provide rows of openings, the openings of each row being spaced transversely of the screen, and the openings of the successive rows being offset progressively longitudinally of the screen in overlapping relation, means for directing a beam of light successively through said openings, and a photo-electric cell sensitive to reflected light from the document through said openings, a printing mechanism associated with said second supporting means and comprising a plurality of printing points arranged over said sheet in positions corresponding to the positions of said openings in said screen, means for reciprocating said points successively in timed relation to the passage of said beam of light through the corresponding openings arranged to cause the points, if unrestrained in their movement, to print on said sheet, means controlled by said photo-electric cell for restraining corresponding points from printing when the light beam striking corresponding openings of said screen pass over unprinted portions of said document, and means for causing relative and synchronous movement between said document and screen and between said sheet and printing device.

11. A machine for producing copies of typewritten, printed and other documents comprising, in combination, a first supporting means for a document to be copied, a second supporting means for a sheet to be printed, a scanning device associated with said first supporting means and comprising a rectangular screen perforated to provide rows of openings, the openings of each row being spaced transversely of the screen, and the openings of the successive rows being offset progressively longitudinally of the screen, means

for directing a beam of light successively through said openings, and a photo-electric cell sensitive to reflected light from the document through said openings, a printing mechanism associated with said second supporting means and comprising a plurality of printing points arranged over said sheet in positions corresponding to the positions of said openings in said screen, an inking medium positioned intermediate said points and said sheet, means for reciprocating said points successively in timed relation to the passage of said beam of light through the corresponding openings arranged to cause the points, if unrestrained in their movement, to print on said sheet, means controlled by said photo-electric cell for restraining corresponding points from printing when the light beam striking corresponding openings of said screen pass over unprinted portions of said document, and means for causing relative and synchronous movement between said document and screen and between said sheet and printing device.

12. A printing mechanism comprising, in combination, a plurality of printing points positioned in a plurality of rows, the points of each row being spaced transversely of a sheet to be printed and the points of successive rows being offset progressively longitudinally of the sheet in overlapping relation, means for reciprocating said printing points successively at a predetermined frequency into printing engagement with said sheet so that during relative movement between said sheet and said points the points, if unrestrained, print over the entire surface of the sheet during a complete unidirectional passage of the sheet past the points, independent means for restraining the printing movement of each point, means for causing relative movement between the sheet and printing points, and an inking medium positioned intermediate the printing points and sheet.

13. A printing mechanism comprising, in combination, a plurality of printing points positioned in a plurality of rows, the points of each row being spaced transversely of a sheet to be printed and the points of successive rows being offset progressively longitudinally of the sheet, means for reciprocating said printing points at a predetermined frequency into printing engagement with said sheet so that during relative movement between said sheet and said points the points, if unrestrained, print over the entire surface of the sheet, independent means for restraining the printing movement of each point, and means for causing relative movement between the sheet and printing points.

14. A reproducing apparatus comprising, in combination, a scanning device having a non-rotating rectangular screen provided with rows of openings, the openings of each row being spaced transversely of the screen and the openings of successive rows being offset progressively longitudinally of the screen in overlapping relation, a photo-electric cell, means for directing a beam of light successively through said openings, and a point printing mechanism comprising a plurality of printing points, one for each opening in said screen, said printing points being spaced to duplicate the arrangement of said screen openings, and means for reciprocating said printing points in accordance with the reflected light from said screen openings controlled by said photo-electric cell.

15. A reproducing apparatus comprising, in combination, a scanning device having a non-

rotating screen provided with rows of openings, the openings of each row being spaced transversely of the screen and the openings of successive rows being offset progressively longitudinally of the screen, means for directing beams of light successively through said openings, and a point printing mechanism comprising a plurality of printing points, one for each opening in said screen, said printing points being spaced to duplicate the arrangement of said screen openings, an inking medium for said points, and means for actuating said printing points in accordance with the reflected light from said screen openings.

16. A reproducing apparatus comprising, in combination, a mechanism for scanning a document to be reproduced, a mechanism for printing a copy of said document on a paper, said scanning mechanism comprising a screen positioned above the document and having a plurality of rows of openings, the openings of each row being spaced transversely of the screen, and the openings of successive rows being offset progressively longitudinally of the screen, a photo-electric cell subjected to reflected light from said openings, and means for directing a beam of light successively through said openings, said printing mechanism comprising a plurality of printing points, one for each of said openings, positioned in a plurality of rows to duplicate the positions of said screen openings, means for actuating said printing points in synchronism with the passage of the light beam through corresponding screen openings comprising a printing magnet, a retarding coil and a return spring for each

point, means for energizing the printing magnets of said points in synchronism with the passage of the light beam through corresponding openings, and means for energizing the retarding coils controlled by said photo-electric cell.

17. In an office appliance for reproducing intelligence on an original sheet to a copy sheet, in combination, a first surface for an original sheet and a second surface for a copy sheet, a screen overlying said first surface and the original sheet thereon for exposing increments of said original sheet for scanning the same, said screen and said first surface being relatively movable with respect to one another, a printing mechanism mounted over said second surface and the copy sheet thereon, said printing mechanism including a plurality of printing points, each of said points being located in a position with respect to said copy sheet to duplicate the position of one of the increments of said original sheet exposed by said screen, said printing points and said second surface being relatively movable with respect to one another, said relative movement being synchronized with the relative movement between said screen and said original sheet on said surfaces, means for scanning said original sheet and means controlled by said scanning means for imparting printing impulses from each increment of exposed intelligence to its respective printing point.
